(57) **CLAIM**

The ornamental design for a scanner for an X-ray tomography diagnosis apparatus, as shown and described.

DESCRIPTION

FIG. 1 is a perspective view of a scanner for an X-ray tomography diagnostic apparatus, showing our new design;

FIG. 2 is a front elevational view thereof;

FIG. 3 is a rear elevational view thereof;

FIG. 4 is a top plan view thereof;

FIG. 5 is a bottom plan view thereof; right-side elevational view thereof;

FIG. 6 is a left-side elevational view thereof; and,

FIG. 7 is a right-side elevational view thereof.

1 Claim, 7 Drawing Sheets
